Patented Aug. 15, 1916.

UNITED STATES PATENT OFFICE.

CHRISTIAN B. CHRISTENSEN, OF SAN FRANCISCO, CALIFORNIA.

RECEPTACLE FOR BOTTLES.

1,194,478.

Specification of Letters Patent. Patented Aug. 15, 1916.

Application filed June 2, 1915. Serial No. 31,750.

To all whom it may concern:

Be it known that I, CHRISTIAN B. CHRISTENSEN, a citizen of the United States, residing at the city of San Francisco, in the county of San Francisco and State of California, have invented certain new and useful Improvements in Receptacles for Bottles, of which the following is a specification.

My invention relates to a receptacle for bottles.

The object of my invention is to provide a receptacle for bottles to preserve them from abstraction and their contents from removal or loss, and my said invention has particular reference to bottles of milk delivered without the premises of consumers.

My invention consists in the combination and arrangement of parts shown in the accompanying drawing, described in the following specification and claimed in the appended claim.

Referring to said drawing the figure shows a section of the device embodying my invention, with the side view of a milk-bottle as contained therein.

In said drawing 2 indicates the top and 3 the bottom of said device 1, which has two oppositely positioned side walls 4. Hinged at 5 is a front door 6 and hinged at 7 is a rear door 8, the said device having when the doors are closed the shape of an oblong box. Within and secured to said receptacle and elevated from its base is a partition 9, having a preferably circular opening 10 to receive a bottle when filled. The door 6 is provided in its lower portion with two upwardly curved locking plates 11 and 12, provided with openings 13 and 14, which are circular and correspond with opening 10. The plate 9 rests between the locking plates 11 and 12 when the door is closed. A handle 15 is secured outwardly to the door 6 for the opening of the same. Hinged at 18 to the door 6 is guide plate 19 having opening 20 to receive the neck of a bottle. The rear door 8 may be secured by a lock 21 secured in the staple 22, which staple is preferably affixed in the base of the device and passes through a slot in said door. I prefer to place the receptacle on the jamb or side of the doorway so that when the door is closed it engages the rear door 8 and pre-

vents its opening, but where this placing is not possible the pad-lock 21 may be used as a means of fastening. Hinged at 16 is a shelf 17, which when lowered may be used to hold an empty bottle to be inserted through the rear door 8. To secure a bottle containing milk, for example, in the receptacle, the door 6 is opened and the neck of the bottle inserted upwardly through opening 20 of the plate 19; then some fingers of the user are inserted between plates 11 and 12 and the base of the bottle held above partition 9 so as to clear said partition, when the door is forced inwardly until such base rests on the partition and the bottle drops through opening 10, thereby securing said door 6 from opening. When the consumer desires to secure the bottle inserted in the receptacle he opens the door of his premises engaging door 8, or removes the pad-lock 21 when the receptacle is placed otherwise than mentioned.

The bottle is to be inserted from below when the first door is open.

I claim:

A receptacle for bottles having an upwardly hinged front door, a hinged guide plate projecting inwardly from said door in the upper portion of said receptacle and having an opening for the neck of a bottle, a fixed partition below said guide plate and projecting inwardly from said front door and having an opening for the body of a bottle, an upwardly curved locking plate fixed to said door having an opening for the body of a bottle above said partition and projecting inwardly from said door, an upwardly curved locking plate fixed to said door having an opening for the body of a bottle below said partition and projecting inwardly from said door, a rear door upwardly hinged to said receptacle, and a shelf hinged inwardly to said front door and positioned between the curved locking plate above said partition and said guide plate.

In testimony whereof I affix my signature in presence of two witnesses.

CHRISTIAN B. CHRISTENSEN.

Witnesses:

R. B. TREAT,

W. C. DUNLAP.
